United States Patent Office.

CHARLES E. MARCHAND, OF DELAWARE CITY, DELAWARE, ASSIGNOR TO
HIGGINS, MARCHAND & CO., OF PHILADELPHIA, PENNSYLVANIA.

Design No. 2,768, dated August 27, 1867.

DESIGN FOR A SPOON.

The Schedule referred to in these Letters Patent and making part of the same.

TO ALL WHOM IT MAY CONCERN:

Be it known that I, CHARLES E. MARCHAND, of Delaware City, New Castle county, Delaware, have invented a new Design for Spoons or forks; and I do hereby declare the following to be a full and exact description of the same, reference being had to the annexed drawings, making a part of this specification, in which—

Figure 1 is a perspective view of my improved spoon.

Figure 2, a sectional view of the handle, showing the depth of the corrugation.

Figure 3, a sectional view of the broad end of the handle, showing the depth of the bead or rim *c*.

My invention consists of a regular corrugation extending along the handle *a* of the spoon, extending into the bowl *b*, and entirely along the narrow part of the handle, and forked at the upper part into a curved bead or rim, *c*, around the end of the handle.

Having thus described my invention, what I claim, and desire to secure by Letters Patent, is—

A new design for spoons or forks, said design consisting in a regular corrugation, extending entirely along the narrow part of the handle, and into the bowl, and then forking into a rim or bead around the broad end of the handle, substantially as described and shown.
